W. Wells,

LASTING MACHINE.

No 41967.

Patented Mar. 15, 1864.

William Wells

UNITED STATES PATENT OFFICE.

WILLIAM WELLS, OF MIDDLETON, ASSIGNOR TO ALFRED B. ELY, OF NEWTON, MASSACHUSETTS.

IMPROVED LASTING-MACHINE.

Specification forming part of Letters Patent No. 41,967, dated March 15, 1864.

To all whom it may concern:

Be it known that I, WILLIAM WELLS, of Middleton, Massachusetts, have invented certain new and useful Improvements in Machines for Lasting Boots and Shoes; and the following, with the accompanying drawings, form a full, perfect, and exact description of the same as regards the construction and operation thereof.

In the construction of lasting-machines the main objects to be obtained are substantially rigid jaws for holding the sides of the upper-leather to the sides of the last, rigid flanges extending over from the jaws for breaking down the edges of the leather over the bottom of the last, and an adjustable holding mechanism for adjusting the last to such heights as may be required by differences of construction and by different thicknesses of leather. The jaws are usually four in number.

In my machine the heel-jaw is stationary. The toe-jaw is movable to and from the last. The side jaws are hung upon pivoted arms or clamps, which swing open to insert the last, and then are closed up and fastened. The last is placed upon a pin or rod, one end of which is inserted into the top of the last, while the other is attached to a lever or device for raising or lowering it to its proper height. To the side jaws are rigidly attached projecting flanges, fitting the bottom of the last and projecting over so as to break down the leather upon the last, where it can be confined for receiving the outer sole. The end jaws are provided with hinged or folding flanges, which are thrown apart when the side jaws are open, but which are closed or folded together over the heel and toe when the side jaws are closed, operating in this manner better than if they were not hinged and were rigidly attached to the end jaws.

In the accompanying drawings, Figure 1 is a top view with the jaws relaxed and the last in place. Fig. 2 is an end view of the hinged flanges. Fig. 3 is a side and a sectional view of a side jaw with flange attached. Fig. 4 is a vertical sectional view as regards the main working parts. Fig. 5 is a view of the wedge-clamp used for closing the side jaws.

A is the last having a hole bored in its top, and placed bottom up on a pin, rod, or stud,

a, which passes through a brace, *a'*, and rests upon the adjusting-lever *J*.

B is the toe-jaw with a recess in and upon it, usually lined with leather, for the toe of the last. This jaw is made to recede from and close up to the last by means of a screw, *b*, with its handle *b'* passing through the collar *b''* in the body of the machine and into the jaw B, which is made to move on ways for the purpose.

C is the heel-jaw, which is stationary, and is usually lined with leather to fit the last.

D D are side frames, arms, or clamps pivoted at *d*, so as to swing off from and up to the last, and having the side jaws, E, fastened to them by a thumb-screw, *e*, passing through the clamp and into the jaw. These jaws are constructed so as to fit the sides of the last up to the bottom edge thereof, which may be accomplished by having them so cast or by having them suitably lined.

F F are the flanges of the side jaws, made of sheet metal and bent so as to conform to the bottom of the last, and securely fastened to the jaws. They may be cast with the jaws.

G G are the heel and toe flanges, each made in two pieces pivoted together, and securely fastened to hinges *g*, moving on the pin *g'*, and placed outside the heel and toe jaws, to which also they are confined. These flanges and hinges are thrown apart by the spring *g''*, and are folded or closed up by the closing up of the side arms or clamps, D D, which press against their sides at *c c*.

H is a clamping-lever, which is pivoted at *h* upon a bolt or rod, *i i*, attached to the upright arms of one of the side clamps D D, and reaching over and beyond the rod *i' i'*, attached to the upright arms of the other side clamp D D. The wedge-point *h'* being crowded down over *i' i'*, closes up the side jaws, and these closing fold up the end flanges.

J is a lever pivoted at *j'*, and upon which the lower end of the rod *a*, which holds the last, rests. By the action of this lever the last is raised or lowered to its proper position for the action of the flanges on the leather.

1 is the outer edge of the bottom of the last or leather. 2 is the inner line of the flanges when they are closed up, and 3 is the inner line of the leather after it is broken down, leav-

ing a space between 2 and 3 in which to insert pegs or nails for confining the leather.

By constructing and attaching my side jaws in the manner I do I am enabled to apply jaws of different sizes to the same side clamps, and so last different-sized shoes in the same machine.

K K K are adjustable gages with slots and screws fitted to the jaws or flanges, against which the outer sole is placed, so that it can be tacked or fastened to the last, and be in readiness to be sewed or pegged upon the shoe the moment it is removed from the machine.

Having thus described my invention, I do not claim the use of what I have denominated "jaws," nor of what I have designated as "flanges," but, in the construction and combination of the mechanism and devices employed by me, what I claim in lasting machines, substantially as and for the purposes described, is—

1. The combination of hinged or folding flanges with the end jaws, heel, and toe.
2. The combination of hinged or folding heel and toe flanges with flanged side jaws.
3. So constructing the parts that the hinged end flanges can be folded together over the last, when in position, by bringing up the side jaws or clamps.
4. Constructing and combining the side clamps and side jaws so as to remove and replace the jaws, as may be required.
5. So constructing the holding mechanism as to adjust the height of the last to the flanges or jaws, substantially as described.
6. The combination of gages with the flanges for fitting on the outer sole.

WILLIAM WELLS.
